FACIAL HEATING PAD

Lawrence Katzman and Robert Dublirer, New York, N.Y.,
assignors to Kaz Manufacturing Co., Inc., New York,
N.Y., a corporation of New York

Filed Jan. 2, 1968, Ser. No. 10,014

Term of patent 14 years

(Cl. D83—1)

FIG. 1

FIG. 3

FIG. 2

FIG. 4

FIG. 5

FIG. 6

FIG. 1 is a front elevational of a facial heating pad showing our new design, the electric cord element is fragmentarily shown in broken lines for ease of illustration; FIG. 2 is a rear elevation thereof;

FIG. 3 is a side elevation as seen from the right of FIG. 1;

FIG. 4 is a side elevation as seen from the left of FIG. 1;

FIG. 5 is a top plan view thereof; and

FIG. 6 is a bottom plan view thereof.

The broken lines around the peripheral edge of the mask are intended to represent conventional closure means.

The dominant features of our design reside in the por-

We claim:

The ornamental design for a facial heating pad, as shown and described.
